UNITED STATES PATENT OFFICE.

JAMES B. GOCKE AND CHARLES F. DE CORSE, OF LOS ANGELES, CALIFORNIA; SAID DE CORSE ASSIGNOR TO SAID GOCKE.

PIPE STRAIGHTENER.

Application filed August 11, 1924. Serial No. 731,376.

The present invention relates to the art of removing indentations and like irregularities from pipe and casing and otherwise restoring them to original form.

5 The principal object of our invention is to provide improved method and means for removing indentations rapidly and easily, preferably so that one man may do the work without the aid of power or heat. It will 10 be understood in the consideration of our invention that the practice now followed is quite tedious and expensive in all its forms. The act of driving wedges, balls and the like through pipe and casing 15 lengths is laborious and inaccurate. Particularly in the case of oil well casing, a slight indentation may render the casing unfitted for use. To restore an indented length of casing it is important, in removing the dent, that the metal be returned to 20 original position without otherwise altering the arrangement of adjacent metal and without weakening or drawing the metal previously distorted.

25 It is, therefore, another and important object of the invention to provide for returning the indented portion to a true round form without exerting a too concentrated force on adjacent portions of the casing.

30 Another object of the invention is to provide simple and dependable means whereby the required force may be applied slowly, and accurately, and at a rate under the control of the operator.

35 Another object of the invention is to provide for removing indentations from pipe regardless of the distance from one end of the pipe to the indentation.

40 Another object of the invention is to provide an apparatus which may be easily and quickly applied to or removed from the pipe being treated.

45 Still other objects and advantages of our invention will appear hereinafter and will be better understood by virtue of the order in which they occur.

50 Briefly stated, our method consists in placing within the pipe, at the point to be corrected, two or more members or shoes having outer curved or arcuate surfaces conforming to the normal contour of the inner perimeter of the pipe. In a complete outfit there will be provided a plurality of sets of shoes so that various standard sizes 55 of pipe may be treated. In conformity with

our invention, one shoe (it is preferable to employ only two shoes) is of a considerably greater area than the other shoe, so that any force acting upon the shoes will distribute itself from the larger shoe over a 60 considerable area. We provide means for holding the shoes oppositely and co-axially aligned so that when the smaller shoe is placed directly under the indentation the larger shoe will rest on that portion of the 65 pipe wall lying opposite to the indented portion. It will be apparent now that by forcing the shoes away from each other the shoe of smaller area will begin to force the depressed metal outwardly while the other 70 shoe will have no effect on the pipe because of the fact that the force which might act through the lower shoe is resisted by being applied over a comparatively large area of pipe wall. This will hold true even under 75 conditions where the indentation is so pronounced that the contained metal has more resistance than other portions of the pipe.

One embodiment of the means for carrying out our method is illustrated by the accompanying drawings, in which—

Figure 1 is a view in side elevation of the said embodiment showing it in operative position within a pipe;

Figure 2 is an enlarged view in vertical 85 section thereof.

Figure 3 is a view in section seen on a line 3—3 of Figure 1;

Figure 4 is a view in section seen on a line 4—4 of Figure 3.

The shoes which comprise a set of two are indicated in the drawings at 6 and 7, respectively, shoe 7 being of greater length and greater width than shoe 6. The latter, which is termed the upper shoe, is provided with a pair of spaced downwardly extending pins 8 for a purpose apparent hereinafter. We refer to the shoe 6 as being the upper shoe merely to identify it in the drawings, it being understood that in using the device being described it is preferable to have the pipe horizontally disposed with the smaller shoe uppermost. However, it will be understood that the device may be used with the pipe in any position, even when vertically suspended in the bore of a well.

As a powerful and convenient means for forcing the shoes apart while holding them suitably positioned within the bore of a pipe, such as 9, we provide a hydraulic cylin- 110

der member 10 and a plunger or ram 11 which is a working fit in said cylinder. In conjunction there is provided a long bar 12 of sufficient length to extend from the point 5 where the shoes are to be operated to a point externally of the pipe. Said bar should be hollow to provide for light weight and may be a length of smaller diameter pipe. The principal requirement for the bar, for all 10 usual working purposes, is that it be rigid and non-revolubly attached to the cylinder, as by welding at 13, so that the shoes may be revolved to accurately position the upper shoe.

15 The plunger is provided with a packing cup 14 so that the space 15 below is pressure tight, and the cylinder is provided with a drilled hole 16 to admit fluid to space 15 from a high pressure fluid tube 17. Said 20 tube is arranged parallel with the bar and is preferably external thereof.

The cylinder is formed with a circular integral bottom flange 18 having a flat under surface 19. The lower shoe, as well as the 25 other sizes of bottom shoes (not shown) is provided with a circular depression 20 into which the flanged portion of the cylinder may fit. The shoe is provided with two lugs 21 and 22, lug 22 being fixed and lug 30 21 being revoluble on the plate of the shoe.

Thereby the lower shoe may be detachably secured to the cylinder member with the lugs engaging the flanged part of the cylinder. The cylinder is provided internally with a 35 pair of spaced inwardly projecting pins 23 and the plunger is accordingly provided with a corresponding pair of apertures 24 into which the pins extend. Thus the plunger is held against revolving in the cylinder.

40 The upper shoe rests directly upon the plunger, which is provided with a pair of apertures 25 into which the pins extend. Thus the upper shoe is held non-revolubly to the plunger while the plunger is held 45 non-revolubly in the cylinder. In attaching the lower shoe 7 to the cylinder, and the bar 12 to the cylinder, the shoe 7 is accurately aligned longitudinally with the bar 12. Thus, when the bar 12 is centered in a 50 large pipe, such as 9, there is excellent assurance that the shoe 7 is properly aligned. The pins 23 and 8 are so positioned that the longitudinal axis of both the shoes 6 and 7 are accurately aligned with each other and 55 with the longitudinal axis of the bar 12.

In order to provide for high fluid pressure to force the shoes apart while they are within a pipe, we provide a pump 26. Preferably the pump is connected with the other parts of the device to provide a complete unit by which the shoes may be hydraulically operated within a pipe by pressure producing means located externally of the pipe.

The pump includes a flat base 27 and a

body 28, the latter being, in this embodiment, a block of steel welded to the base. Said body is provided with a vertical bore 30 intersected by a transverse suction bore 31 and a similar discharge bore 32. The vertical bore is fitted with a small diameter plunger 33 and the transverse bores are provided with ball checks 34 and 35, respectively, to provide for drawing oil from a small reservoir 36 and discharging same into the pressure line at high pressure. The pump body is located about centrally of the base longitudinally while at the forward end of the base there is welded a common T fitting 37. The bar or pipe, which connects the hydraulic press with the pump, is permanently attached to the fitting so that all parts may be handled as a single unit. The plunger is provided with a packing gland 38 and said plunger is increased in diameter as at 39 and pivotally connects with a pump lever 40 as at 41. The handle end 42 of the lever is extended rearwardly a considerable distance to provide powerful leverage. The forward end 43 of the lever is pivotally connected as at 44 to a link 45. The T is provided with a transverse pin 46 which provides an anchor for the link, the latter being provided with an aperture 47 through which the pin extends.

From the suction bore a short suction line 48 leads to the reservoir, while the discharge line is connected directly with the discharge bore. A by-pass line 49 is provided which is connected with the pressure line by a T 50 and to the suction line by another T 51. A valve 52 is provided in said by-pass line. When the valve is open the pump will be incapable of building up a fluid pressure in the high pressure line because the fluid will take the line of least resistance and flow back to the reservoir.

The operation of the embodiment just described, and the manner in which our improved method is carried out will be better understood from the following: A length of casing 9 possesses an indentation 54 which it is desired to remove by forcing the metal back to original position. The correct size of upper and lower shoe is selected and fitted to the plunger and cylinder respectively. Now the entire device with the shoe attached may be handled as a single unit and advanced into the casing. Preferably the casing is arranged so that the indentation is uppermost but in case it is not convenient to have the casing so positioned, then the device may be turned, after it is in the pipe, to bring the lower shoe directly under the indented portion. The rigid pipe connecting the shoes with the pump, which is always kept externally of the casing, provides for accurately positioning the shoes and for retracting same from the casing when the job is finished.

With the shoes correctly located the pump lever is manipulated and slowly oil is pumped into the cylinder to raise the pressure. The long pump lever in conjunction with the small plunger provides for producing very high hydraulic pressures. Slowly, accurately, and with great force, the shoes are gradually moved away from each other, relatively. The lower shoe is of such area in contact with the pipe that it merely provides a fixed base against which the pressure is exerted to force the smaller shoe upward. The pump is operated until they are the correct distance apart to return the metal to original contour. To relieve the pressure the valve in the by-pass line is opened and the fluid will flow back to the reservoir and permit the upper shoe to descend so that the entire device may be withdrawn from the casing.

It will be apparent now that with our method and suitable means, pipe and casing may be repaired, regardless of location. Heavy casing sections may be treated even in otherwise inconvenient positions such as on the ground or on a rack, and, in fact, any place where it is possible to insert the device described.

While we have shown and described specific procedure in carrying out our invention and have described a specific embodiment of means for carrying out our invention, we do not limit ourselves thereto, nor do we limit ourselves to any construction or arrangement of parts for same, and we may alter the construction and arrangement of parts as occasion seems to require without enlarging the scope of the present invention within the appended claim.

We claim as our invention:

In a device of the character described, a pump body, a rigid rod projecting from said body, a cylinder rigidly fixed to the outer end of said rod, a convex shoe rigidly attached at the lower end of said cylinder with its longitudinal axis paralleling the longitudinal axis of the rod, a piston reciprocal in said cylinder, means carried by the cylinder to prevent the piston from turning therein, and a convex shoe non-revolubly fixed to the upper end of the piston; said means acting to hold the upper shoe so that its longitudinal axis parallels the longitudinal axis of the lower shoe.

JAMES B. GOCKE.
